DESIGN FOR A HAT

Tina Leser, New York, N. Y.

Application March 13, 1941, Serial No. 99,554

Term of patent 3½ years

To all whom it may concern:

Be it known that I, Tina Leser, a citizen of the United States, residing in New York city, in the county of New York and State of New York, have invented a new, original, and ornamental Design for Hats, of which the following is a specification, reference being had to the accompanying drawing, forming part thereof, in which—

The characteristic feature of my design resides in the combination on the specific hat disclosed of the net hat band trimmed as shown.

I claim:

The ornamental design for a hat, as shown and described.

TINA LESER.
